Inventor:
Barne O. Thompson

United States Patent Office.

BJARNE O. THOMPSON, OF CHICAGO, ILLINOIS.

Letters Patent No. 91,794, dated June 22, 1869.

COMBINED CLOTHES-WRINGER AND MANGLE.

The Schedule referred to in these Letters Patent and making part of the same.

To all whom it may concern:

Be it known that I, BJARNE O. THOMPSON, of the city of Chicago, in the State of Illinois, have invented certain new and useful Improvements in Mangles and Wringers; and I do declare that the following is a full, clear, and exact description thereof, reference being had to the accompanying drawings, making part of this specification, in which—

Figure 1 is a rear elevation.

Figure 2, an outside view of one of the posts and the bottom-support.

Figure 3, an inside view of one of the posts.

Figures 4, 5, 6, 7, details.

To enable others skilled in the art to make and use my invention, I proceed to describe the construction of the same.

A A' B C D represent the frame and supporting pieces, which are constructed in the usual manner.

On the inside, and near the top of the standards, or posts A A', is a long groove, k, fig. 3, in which the irons C are inserted and move up and down.

a is an iron plate, secured to these posts over this groove, or recess; but before being fastened thereto, the iron c is placed in proper position, the portion d extending inward, as shown, c being wider than the slot, or opening seen at k, in the plate a.

b b' are slots, or openings in the posts, through which the journals of the cylinders are inserted.

The upper cylinder is supported at each end in the hole n, near the lower ends of the irons c.

The form of this iron c will be seen in figs. 4, 5, 6, being three views of the same. It consists of a single piece, c d, bent at right angles, the horizontal portion d having a flange on each side, and a slot, m, in the bottom.

F is a spring, which may be of wood or metal. The

ends of this spring rest upon d, between the flanges thereon, and a pin, having a head or screw, is inserted in the spring, at or near each end, and on the under side, passing through the slot m, and so arranged as to move therein.

This spring can be tightened or loosened by means of the screw l, operated by the crank e.

As the spring F is raised, the cylinder E will be also raised, as the spring cannot be withdrawn from d in consequence of the screw, or headed pin s.

On each end of each cylinder, I place a piece of rubber, G, such as is used upon clothes-wringers, about six inches long, so that this portion of the machine can be used as a clothes-wringer, the remaining part being used as a mangle.

The cylinders are of wood, and I usually make them about two feet nine inches long and about three inches in diameter.

f is the crank for operating the mangle, on which is an arm, g, pivoted, which has a projection, i, near the upper end, which enters a hole in the end of the journal upon which the crank is placed, and the rod, or arm g, is held in place by the spring h.

When it is desired to remove the crank, it can be done by pressing back the spring h and arm g, so as to withdraw the pin i from the journal.

What I claim as my invention, is—

The construction of the rollers, a portion of each being constructed of India rubber, for a wringer, and a portion of wood, or other hard material, for a mangle, in combination with the frame and other devices, as arranged and shown.

BJARNE O. THOMPSON.
